DELTA ELECTRIC COMPANY, OF MARION, INDIANA, A CORPORATION OF INDIANA.

PORTABLE ELECTRIC LAMP.

1,295,497.

Specification of Letters Patent.

Patented Feb. 25, 1919.

Application filed September 30, 1916. Serial No. 122,961.

To all whom it may concern:

Be it known that we, HARRY HENDERSON and ARTHUR E. CASE, both citizens of the United States, and residents of Marion, in ⁵ the county of Grant and State of Indiana, respectively, have invented certain new and useful Improvements in Portable Electric Lamps, of which the following is a full, clear, and exact description.

¹⁰ The invention relates to portable electric lamps and its object is to provide a lamp of this type which is simple in construction and can be produced at a low cost.

The invention consists in the several novel ¹⁵ features hereinafter set forth and more particularly defined by claims at the conclusion hereof.

In the drawings: Figure 1 is a side elevation of a lamp embodying the invention. ²⁰ Fig. 2 is a longitudinal section on a somewhat larger scale. Fig. 3 is a plan of a blank from which the tubular lamp body is formed. Fig. 4 is a section taken on line 4—4 of Fig. 2. Fig. 5 is an inner face view ²⁵ of the removable cap at one end of the lamp body. Fig. 6 is a section on line 6—6 of Fig. 5. Fig. 7 is a section taken on line 7—7 of Fig. 5.

The lamp comprises a tubular body 8, a ³⁰ hood 9 at one end of the body and containing a light reflector 10, a lens 11, a lens-retaining ring 12, and a cap 14 for closing the other end of the body. All of these parts, except the lens are formed of sheet ³⁵ metal. Hood 9 is formed of a single piece of metal, is cup-shaped and comprises an annular wall 15^a and a wall 15 which forms one end of the tubular body 8. An incandescent lamp socket 16 is secured in said ⁴⁰ wall 15. An incandescent lamp 17 of usual construction is screw-threaded into the socket and has the usual base 18 forming one of the lamp-contacts and tip-contact 19. The body 8 is cylindrical and adapted and ⁴⁵ formed to contain a dry-battery 20 which is provided with a pole-piece 21 at one end which is adapted to contact with the tip contact 19 of the lamp. Cap 14 is cup-shaped and has a flange 14' which fits around one ⁵⁰ end portion of the body 8. This flange 14' is formed with angular indentations, as at 22, to form grooves to receive and hold indentations 23 on the tubular body 8. This construction forms a bayonet catch which

permits the cap to be readily removed and ⁵⁵ replaced as is desirable in replacing the dry battery and in which the catch-parts are integral with body and cap respectively. The end of cap 14 is provided with struck-up tongues 24 which are adapted to pass ⁶⁰ through a plate of insulation 25 and secure it to the cap. A conductor-strip 26 on the inner face of the insulating plate 25 has integral struck-up tongues 27 which extend through holes 28 which are formed in the ⁶⁵ insulating plate to secure this strip in the cap. The ends of the tongues 27 are held in countersunk portions 27^a of the insulating plate so that they will not contact with the end of the cap. A coil spring 29, the inner ⁷⁰ end of which is adapted to contact with the usual pole piece on the lower end of the battery 20, has one of its coils extended between the strip 26 and the inner face of the insulating plate 25 and is secured in position so that it will be removable with the cap by strip 26. The outer ends of strip 26 are bent toward the end of the cap, as at ⁷⁵ 30, to form contact-surfaces for a switch-strip 31 which is slidably held in the body 8 so that it can be shifted into or out of engagement with one of the terminals 30. When strip 31 engages the terminal 30, a circuit will be established as follows: pole piece 21, tip-contact 19, lamp 17, lamp-base ⁸⁰ 18, socket 16, hood 9, body 8, strip 31, strip 26 which is insulated from cap 14, spring 29 and the lower pole of the battery.

The body 8 is formed of a single sheet of ⁸⁵ metal as shown in Fig. 3, the margins of which are provided with interfitting dovetailed tongues 33 and notches 34 and also with integral tongues 35 which are inserted through slots 36 in the wall 15 of the hood 9 and clenched on the inside thereof, as at 37, ⁹⁰ to securely unite the hood and body. This attachment also serves to hold the body blank in tubular form. When the blank has been bent to form a tubular body, the interfitting tongues are flush with one another so that there is no objectionable excrescence on the periphery of the body. The switch-strip 31 is formed of a flat strip of metal, one end of which is extended through a notch 39 adjacent one end of the body to guide said ⁹⁵ 100 end positively into and out of engagement with one of the contact terminals 30 of the conductor strip 26. Adjacent the other end,

the strip 31 extends through a slot 41 in the body and is provided with an off-set portion 40 outside of the body which serves as a handle or finger-piece for shifting the 5 switch strip. The portion 40 disposed outside of the slot 41 is slightly wider than the slot, and a terminal 42 of said strip is extended longitudinally in the body. As a result, the strip, which is formed of a single 10 piece of metal, can be inserted through the slot 41 and the portions inside of the body can be bent. This saves the cost of additional parts for guiding the strip and exemplifies a switch strip guided in the case 15 and formed of a single piece of metal. Indentations 23 in the body and angular indented portions 22 exemplify a quick detachable connection between the cap and the body which is formed without additional pieces 20 of material.

The invention exemplifies a portable flash lamp which can be produced at an exceptionally low cost and is simple in construction.

26 The invention is not to be understood as restricted to the details set forth, since these may be modified within the scope of the appended claims, without departing from the spirit and scope of the invention.

30 Having thus described the invention, what we claim as new and desire to secure by Letters Patent, is:

1. In a portable electric lamp, the combination of a metallic body formed of a sheet 35 of metal having its margins provided with interfitting and interlocking tongues and notches, said body adapted to contain a battery, a hood mounted at one end of said body and holding said body in assembled 40 form, a lamp within said hood, and a cap detachably mounted at the other end of said body:

2. In a portable electric lamp, the combination of a metallic body formed of a sheet 45 of metal having its margins provided with interfitting and interlocking tongues and notches, said body adapted to contain a battery, a hood mounted at one end of said body and holding said body in assembled 50 form, a lamp within said hood, a cap detachably mounted at the other end of said body, and means for establishing a circuit from the battery through the lamp.

3. In a portable electric lamp, the combination of a tubular metallic body formed of a sheet of metal and having interfitting and interlocking tongues and notches and adapted to contain a battery, a hood mounted at one end of said body and holding said body 60 in tubular form, a lamp within said hood, a cap detachably mounted at the other end of said body, and means for establishing a circuit from the battery through the lamp.

4. In a portable electric lamp, the combination of a metallic body formed of a sheet

of metal having its margins provided with interfitting and interlocking tongues and notches and adapted to contain a battery, a hood at the end of said body connected thereto by tongue and slot connections, a 70 lamp mounted in the hood, and a cap detachably connected to the other end of the body.

5. In a portable electric lamp, the combination of a metallic body formed of a sheet 75 of metal having its margins provided with interfitting and interlocking tongues and notches and adapted to contain a battery, a hood at the end of said body connected thereto by tongue and slot connections, a lamp mounted in the hood, a cap detachably connected to the other end of the body, 80 and means for establishing a circuit through the battery and the lamp.

6. In a portable electric lamp, the combination of a tubular metallic body adapted 85 to contain a dry battery, a lamp mounted at one end of the body and having its base electrically connected to the body, a cap detachably connected to the other end of the metallic body, an insulating member fitting 90 against the inner face of the cap, the cap being provided with struck-up tongues extended through the insulation securing the cap and insulation together, a conductor-strip secured to the insulating member, means for connecting the conductor strip to one pole of the battery, and a switch strip mounted on the body and movable into contact with said conductor strip.

7. In a portable electric lamp, the combination of a tubular metallic body adapted 100 to contain a dry battery, a lamp mounted at one end of the body and having its base electrically connected to the body, a cap detachably connected to the other end of the 105 metallic body, an insulating member fitting against and secured to the inner face of the cap, a conductor plate provided with struck-up tongues securing the plate and insulating member together, means for connecting 110 the conductor strip to one pole of the battery, and a switch strip mounted on the body and movable into contact with said conductor strip.

8. In a portable electric lamp, the combination of a tubular metallic body adapted 115 to contain a dry battery and having a slot therein, a lamp mounted at one end of the body and having its base electrically connected to the body, a cap detachably connected to the other end of the metallic body, a conductor strip mounted in and insulated from the cap, and a switch strip slidably mounted in the body, having an integral portion extending through said slot and integral enlarged handle portion on the outside of the case lapping the sides of the slot 120 so that the strip will be self-retained in the case.

9. In a portable electric lamp, the combi- 125

nation of a tubular metallic body adapted to contain a dry battery having a slot at one end and a centrally disposed slot, a lamp mounted at one end of the body and having its base electrically connected to the body, a cap detachably connected to the other end of the metallic body, a conductor strip mounted in and insulated from the cap, and

a one-piece switch strip slidably mounted in the slots in the body extending through the case, and having an integral enlarged handle portion on the outside of the case lapsing the sides of the slot. 10

HARRY HENDERSON,
ARTHUR E. CASE.
